UNITED STATES PATENT OFFICE.

JAMES A. HORTON, OF PROVIDENCE, RHODE ISLAND, ASSIGNOR TO IRO-
QUOIS MACHINE COMPANY, OF NEW YORK, N. Y., A CORPORATION OF
NEW YORK.

MACHINE FOR FORMING WIRE-DRAWING DIES.

No. 796,726.

Specification of Letters Patent.

Patented Aug. 8, 1905.

Application filed October 28, 1904. Serial No. 250,372.

To all whom it may concern:

Be it known that I, JAMES A. HORTON, of Providence, in the county of Providence and State of Rhode Island, have invented certain new and useful Improvements in Machines for Forming Wire-Drawing Dies, of which the following is a specification.

This invention relates to the formation in a block or body of steel or other suitable metal of a tapering or conical orifice, the smaller end of which constitutes the throat or acting portion of a wire-drawing die. The wire to be drawn or reduced is passed through said orifice, the wire on entering the die being of larger diameter than the orifice and emerging from the die reduced to the exact diameter of the orifice. The friction of the wire against the wall of the orifice, particularly in drawing iron and steel wire, causes a gradual enlargement of the orifice, so that it is necessary to reform the orifice after the drawing of every coil of wire to restore the orifice to the exact diameter desired. This reforming operation has heretofore been performed practically as follows: The orifice of the die is first scraped by a reamer to remove grit and dirt. The face of the die is then hammered to condense the metal, and thus contract the orifice at its smaller end, the orifice being thus partly closed and its symmetry destroyed. The orifice is then swaged to give it the exact circular form and diameter required by inserting in it by hand a tapered swaging-tool or driving-punch and applying a hand-operated hammer to said tool until the orifice is sufficiently enlarged and properly formed. This operation requires the services of a skilled operator and the expenditure of considerable time, it being necessary to frequently remove the driving-punch and apply a standard plug or gage of the exact size that the orifice is to have in order that the workman may ascertain when the orifice has been sufficiently enlarged, great care being required to avoid an excessive enlargement of the orifice. If the orifice is unduly enlarged, the die has to be rehammered to reduce the size of the orifice and then the swaging operation has to be repeated.

My invention has for its object to simplify and reduce the cost of forming or reforming the orifice of a wire-drawing die and to reduce to the minimum the employment of skilled

labor in the operation, my invention contemplating the employment of mechanism which is largely automatic in its action as a substitute for skilled handwork.

To these ends the invention consists in the improvements which I will now proceed to describe and claim.

Of the accompanying drawings, forming a part of this specification, Figure 1 represents a front elevation of a die-swaging machine embodying my invention. Fig. 2 represents a section on line 2 2 of Fig. 1. Fig. 3 represents a view similar to Fig. 2, showing certain parts in different positions. Fig. 4 represents a section on line 4 4 of Fig. 3. Fig. 5 represents a section on line 5 5 of Fig. 4. Fig. 6 represents a section on line 6 6 of Fig. 5. Fig. 7 represents a section on line 7 7 of Fig. 3. Fig. 8 represents a side elevation of the machine, parts being positioned as shown in Fig. 3. Fig. 9 represents a section on line 9 9 of Fig. 3. Fig. 10 represents an enlarged side elevation of the swaging-tool. Fig. 11 represents a front elevation showing means for rapidly rotating the forming-tool. Fig. 12 represents an end elevation, partly in section, showing the tool-rotating means shown in Fig. 11. Fig. 13 represents a side view of a forming-tool made as a reamer. Fig. 14 represents a section on line 14 14 of Fig. 13.

The same reference characters indicate the same parts in all the figures.

In the drawings and referring for the present to Figs. 1 to 10, inclusive, 12 represents an anvil or support on which bears the die-block 13 to be treated.

14 represents a tapered swaging-tool, the acting portion of which is substantially conical, its sides being preferably slightly concaved lengthwise, as shown in Fig. 10. The concavity of the sides of the tool results in the formation of an attenuated and very slightly tapered end portion, which I find to be advantageous in the operation of the machine. The die-block 13 is originally provided with a tapering or frusto-conical passage 15, extending through the block, its smaller end 15' constituting the throat or acting portion of the die. One of the said parts, called the "die-support" and "swaging-tool," is given a reciprocating movement to intermittently apply the tool to the die and cause the tapered tool to exert a hammering.

or forming action on the wall of the die-throat, it being obvious that the hammering action caused by the reciprocating movement of one of said parts relatively to the other will cause the wall of the throat to conform to the tapered surface of the tool and that the extent to which the tool enters the die-throat will determine the diameter of the throat.

One of the parts 12 and 14—namely, the part which is not reciprocated—is given a progressive movement during the hammering or forming operation to cause a gradual or progressive action of the tool in hammering or forming the throat and prevent the tool from sticking or binding in the die, the said progressive movement being such as to cause the swaging-tool to enter the die more deeply at each successive blow.

In the embodiment of my invention here shown the swaging-tool is the part which is reciprocated and the die-support 12 is the part which is progressively moved or adjusted to make the action of the tool progressive.

16 represents a tool-holder having means, such as a socket 17 and a set-screw 18, for detachably holding the swaging-tool. The said tool-holder is mounted in a reciprocating carrier 19, which is movable in guides 20 20 on the frame of the machine and is provided with a cross-head 21, having an opening in which a bearing-block 22, composed, preferably, of two sections, is adapted to slide. The said bearing-block engages a crank or eccentric 23, formed on a shaft 24, which is journaled in bearings in the supporting-frame and is rotated by power applied to a driving-pulley 26, mounted on said shaft. The rotation of the shaft causes the eccentric 23 to reciprocate the tool-carrier 19, the bearing-block 22 sliding in the slot or opening of the cross-head 21 on said carrier.

The die-block 13 may be detachably held upon the anvil or support 12 by any suitable means, such as a resilient arm 27, attached at one end to the support 12 and overhanging the die-block, said arm having a convex boss 28, Fig. 9, formed on its under side, adapted to enter the larger end of the die-passage 15 and to hold the smaller end or throat of said passage in alinement with the center of the swaging-tool 14, the said arm having an orifice 29 adapted to receive the swaging-tool, as shown in Fig. 9. The die-support 12 is provided with a central orifice 30, which receives a projecting point of the swaging-tool when the latter projects below the die.

The die-support 12 is adapted to have a quick movement toward and from the swaging-tool to permit the die to be moved downwardly out of the path of the said tool, as shown in Fig. 2, or upwardly into said path, as shown in Fig. 3. This quick adjustment facilitates the application and removal of the die and is independent of the progressive adjustment of the die which takes place during

the forming or hammering operation. The means for effecting the described quick adjustment of the die-support comprise a carrier 31, which is movable in fixed guides 32 32 on the frame of the machine and is prevented from rotating in said guides by means of a key or feather 33, affixed to the carrier and moving in a slot or keyway in one of the guides 32.

34 represents a trundle-roll journaled in ears on the lower end of the carrier 31, and 35 represents a cam affixed to a rock-shaft 36, journaled in bearings on the frame of the machine, the said cam supporting the trundle-roll 34, carrier 31, and die-support 12. When the cam is in the position shown in Fig. 2, the carrier 31 is depressed, and when the cam is in the position shown in Fig. 3 the said carrier is raised. Suitable means controlled by the operator are employed for holding the cam 35 in either of said positions, said means comprising in this instance a treadle, (not shown,) an arm 37, affixed to the rock-shaft 36, and a rod 38, connecting said arm with the treadle.

The means for effecting the above-described progressive adjustment of the die-holder are as follows: 39 represents a shank formed on or affixed to the die-support 12 and extending downwardly therefrom into the carrier 31, the latter being socketed to receive the said shank. A screw-thread 40 is formed on the shank 39 and with this screw-thread engages a nut 41. The carrier 31 comprises two parts or sections separated by a space which receives the nut 41, as shown in Figs. 2 and 3, said parts or sections being rigidly connected by a U-shaped neck 42. It will be seen that the rotation of the nut 41 causes an endwise movement of the shank 39 and an adjustment of the die-support 12 toward or from the swaging-tool. It will also be seen that by rotating the nut 41 step by step, the nut being given relatively short movements at each step, the die may be given an extremely fine or micrometric progressive movement or adjustment toward the swaging-tool.

In the operation of the machine a master-die, the orifice of which is of the standard size and shape, is applied to the support 12 when the latter is depressed, and the support and master-die are then raised, as shown in Fig. 3, while the swaging-tool is depressed or in its lowest position until the wall of the orifice of the master-die comes to a bearing or is seated on the tapered portion of the tool, the latter accurately fitting the die-orifice. This upward movement of the die-support is caused partly by the described means for imparting a quick upward movement to the die-holder and partly by the rotation of the nut 41. When the master-die has been thus moved to an adjusted position, a stop member 43, adjustably secured to the nut 41, is adjusted to bear against a fixed stop mem-

ber 430, arranged to prevent further rotation of the nut in the direction required to raise the work-support, provision being thus made for so arresting the upward movement of a die subsequently applied to the work-support in place of the master-die as to insure the same entrance of the swaging-tool into the substituted die as into the master-die. The work-support is then lowered, the master-die is removed, and a die requiring the action of the swaging-tool is applied to the work-support in place of the master-die. The work-support and die are then raised to present the die to the swaging-tool, the upward movement during the swaging action being caused by the step-by-step rotation of the nut caused by the operator. This rotation continues until the stop member 43 abuts against the fixed stop member 430, the die then reaching the height required to cause the exact predetermined entrance of the swaging-tool into the die, and therefore the formation of a throat of the exact size required. It will be seen, therefore, that the die under treatment is automatically arrested in the exact adjusted position of the master-die.

As here shown, the stop 43 is a handle adjustably secured to the nut 41, and the fixed stop 430 is a part of the frame of the machine. The handle abuts against said stop, as indicated by dotted lines in Fig. 7, and thus limits the movement of the nut 41 in the direction required to raise or move the die-support 12 toward the swaging-tool. The handle 43 may be adjustably secured to the nut by means of a jaw 44, Fig. 2, secured to the handle by a screw 45, the said jaw having a projection 46, which engages the under side of an inwardly-projecting tip or flange 47, formed on the nut. When the screw 45 is turned in one direction, it causes the projection 46 to bind on the flange 47, and thus secure the handle 43 to the nut. When the screw is loosened, the handle and jaw may be moved to any desired part of the nut. The handle is provided with a ring 48, which encircles the hub portion of the nut. It will be seen that the adjustability of the member 43 enables the position of the die at the end of the swaging operation to be varied, so that the projection of the swaging-tool through the die may be greater or less, according to the size of wire which the die is intended to produce.

The holder 16 of the swaging-tool is preferably adapted to rotate in the carrier 19 and is preferably rotated automatically step by step during the swaging operation to insure accuracy in the formation of the throat and compensate for any slight deviation from an exact circular form in the cross-section of the acting portion of the swaging-tool. To this end the upper end of the tool-holder 16 is provided with a ratchet-wheel 49, Fig. 6, which is engaged by a pawl 50, pivoted to a slide

51, which is movable in a guide formed for its reception in the cross-head 21. The said slide is provided with projections 52 52, located at opposite sides of the bearing-block 22, as shown in Fig. 5. The revolution of the eccentric 23 causes the bearing-block 22 to reciprocate in the cross-head, and thus strike the projections 52 alternately and reciprocate the slide 51 and pawl 50, thus imparting a step-by-step rotation to the ratchet 49 and tool-holder 16. A stop-pawl 53, Fig. 6, prevents backward rotation of the ratchet and tool-holder.

It will be seen that the operation of the machine is largely automatic, the operator having only to apply the die to the support 12, raise the same to the extent provided by the cam 35, and rotate the nut step by step to the predetermined extent determined by the adjustment of the handle, the result being the formation of a throat in the die of the exact predetermined size and of perfect shape.

The mechanism for reciprocating the swaging-tool, the mechanism for progressively moving or adjusting the die-support, and the stop members which limit the progressive movement or adjustment of the die-support collectively constitute means for so changing the relative positions of the tool and die as to percussively apply the swaging-tool to the die-throat and cause a limited swaging action to the tool on the die, or, in other words, a limited predetermined entrance of the tool into the die to give the die-throat an exact predetermined diameter. I believe myself to be the first to provide a die-swaging machine having coöperative elements or parts constituting means for causing such limited swaging action. I do not, therefore, limit myself to the specific devices and details of mechanism employed in this embodiment of my invention to cause the said limited swaging action, as various other devices and mechanical contrivances may be employed for this purpose without departing from the spirit of my invention.

The adjustable stop member 43 and the fixed stop member 430 coöperate as above set forth in giving the said limited swaging action an adjustable limit to regulate the diameter of the die-throat; but it is obvious that other means may be used for this purpose.

My invention is not limited to a machine in which the forming-tool is a swaging-tool. In Figs. 11 and 12 I have shown the tool-holder 160 provided with a reamer 140 having the same form as the swaging-tool 14, excepting that its tapered acting portion is polygonal in cross-section and has a series of (preferably) four faces, which meet to form inclined cutting edges or angles. Means are also shown for rapidly rotating the said holder and the forming-tool, the latter forming the die-orifice by a cutting or reaming action instead of a swaging action. The means here shown for

rotating the tool-holder 160 comprise a pulley 161, affixed to said holder, and a belt 162, driven by a pulley 163 on the shaft 164, said belt being guided by idle pulleys 165. The shaft 164 is or may be provided with a driving-pulley 265, belted to the pulley 26, which rotates the shaft 24. The pulley 163 may be loose on the shaft 164 and detachably connected therewith by a clutch 166, as shown in Fig. 11. When the pulley 163 is engaged with the shaft, a relatively rapid rotation is imparted to the tool-holder, and the reamer 140 is caused to form the die-orifice, the operation being in all other respects as hereinbefore described, although, if desired, the reciprocating movement of the tool-holder may be discontinued when a reamer is employed. This is not essential, however, as the reamer if reciprocated endwise will have the same forming effect that it would have if it rotated without reciprocating and will permit the removed metal to fall from the tool, thus greatly reducing the strain on the tool.

Having thus explained the nature of my invention and described a way of constructing and using the same, although without having attempted to set forth all the forms in which it may be embodied or all the modes of its use, I declare that what I claim is—

1. A die-forming machine comprising a die-support, a tapered forming-tool adapted to enter a die on said support, means for intermittently applying the tool to a die, and means for making the action of the tool progressive.

2. A die-forming machine comprising a die-support, a tapered forming-tool adapted to enter a die on said support, means for intermittently applying the tool to the die, means for making the intermittent action of the tool progressive, and means for arresting the progressive action to produce a die-orifice of a predetermined size.

3. A die-forming machine comprising a die-support, a tapered forming-tool adapted to enter a die on said support, means for intermittently applying the tool to the die, means for making the intermittent action of the tool progressive, and adjustable arresting means for limiting the progressive action and determining the size of the die-orifice.

4. A die-forming machine comprising a die-support, a tapered swaging-tool adapted to enter a die on said support, means for causing a swaging action of the tool, means for making said action progressive, and means for causing rotative changes of position of the tool relatively to the die on which it acts.

5. A die-forming machine comprising a die-support, a tapered swaging-tool adapted to enter a die on said support, means for causing a swaging action of the tool, means for making said action progressive, and means for rotating the tool.

6. A die-forming machine comprising a die-support, a tapered swaging-tool adapted to

enter a die on said support, means for imparting a reciprocating swaging movement to one of said parts, and means for making the swaging action progressive.

7. A die-forming machine comprising a die-support, a tapered swaging-tool adapted to enter a die on said support, means for imparting a reciprocating swaging movement to one of said parts, means for making the swaging action progressive, and means for arresting the progressive action.

8. A die-forming machine comprising a die-support, a tapered forming-tool adapted to enter a die on said support, means for reciprocating the said tool to cause a forming action, means for progressively moving or adjusting the die-support to extend the forming action, and means for limiting said progressive movement.

9. A die-forming machine comprising a die-support, a tapered swaging-tool adapted to enter a die on said support, automatic means for reciprocating the said tool to cause a swaging action, means controlled by an operator for progressively moving or adjusting the die-support to extend the swaging action, and means for limiting said progressive movement.

10. A die-forming machine comprising a die-support, a tapered reciprocating forming-tool adapted to enter a die on said support, means for giving the die-support a quick adjustment to move the die into and out of the path of the tool, means for giving the said support a micrometric movement to extend the forming action, and means for limiting said movement.

11. A die-forming machine comprising a tapered forming-tool adapted to enter a die, means for intermittently applying the tool to the die, a die-support having a screw-threaded shank, an adjusting-nut engaged with said shank, and a support for said shank and nut.

12. A die-forming machine comprising a tapered forming-tool adapted to enter a die, means for intermittently applying the tool to the die, a die-support having a screw-threaded shank, an adjusting-nut engaged with said shank, a support for said shank and nut, and means for limiting the adjusting movement of the nut.

13. A die-forming machine comprising a tapered forming-tool adapted to enter a die, means for intermittently applying the tool to the die, a die-support having a screw-threaded shank, an adjusting-nut engaged with said shank, a support for said shank and nut, and adjustable means for limiting the adjusting movement of the nut.

14. A die-forming machine comprising a tapered forming-tool adapted to enter a die, means for intermittently applying the tool to the die, a die-support having a screw-threaded shank, an adjusting-nut engaged with said shank, a support for said shank and nut, a stop member adjustably secured to the nut, and

a fixed stop member to coöperate with said arm in limiting the adjusting movement of the nut.

15. A die-forming machine comprising a tapered forming-tool adapted to enter a die, means for intermittently applying the tool to the die, a carrier movable toward and from said tool, a die-support adjustably connected with the carrier, and means for moving said carrier and die-support in unison toward and from the tool.

16. A die-forming machine comprising a tapered forming-tool adapted to enter a die, means for intermittently applying the tool to the die, a carrier movable toward and from said tool, a die-support adjustably connected with the carrier, a cam supporting said carrier, and means for oscillating said cam to raise and depress the carrier.

17. A die-forming machine comprising a tapered forming-tool, a die-support carrier composed of two rigidly-connected parts or sections, a die-support having a screw-threaded shank movable in said carrier, a nut located between the parts of the carrier and engaged with said shank, and means for moving the carrier toward and from the forming-tool.

18. In a die-forming machine, a die-support or anvil, a tapered die-forming tool adapted to enter a die on said support, means for intermittently applying the tool to the die, and means for locating the die on the anvil with the die-orifice in alignment with the tool.

19. In a die-forming machine, a tapered die-forming tool, and a die-support or anvil having an overhanging resilient arm provided with a boss to engage and center a die-cavity, and an opening for the reception of the forming-tool.

20. A die-forming machine comprising a swaging-tool holder, a carrier in which said holder is rotatively mounted, mechanism including a sliding block for reciprocating the carrier, and means operated by the movements of said block for rotating the tool-holder.

21. A die-forming machine comprising a

swaging-tool holder, a carrier in which said holder is rotatively mounted, said carrier having a cross-head, a bearing-block slidable in said cross-head, a driving-shaft having an eccentric engaged with said block, and a slide movable on said cross-head and having projections in the path of said bearing-block, and a pawl engaging a ratchet affixed to the tool-holder.

22. A die-forming machine comprising a tapered swaging-tool adapted to enter a die, means for supporting a die with its throat in the path of the tool, means for applying said tool percussively to the die-throat, and means for limiting the entrance of the tool into said throat.

23. A die-forming machine comprising a tapered swaging-tool adapted to enter a die, means for supporting a die with its throat in the path of the tool, means for applying said tool percussively to the die-throat, and adjustable means for limiting the entrance of the tool into said throat.

24. A die-forming machine comprising a reciprocating forming-tool, a die-support adapted to engage a master-die, means for moving the die-support lengthwise of the path of the tool to give the master-die an adjusted position with the wall of its orifice seated on the forming portion of the tool, a fixed stop member, and a complementary stop member movable with the die-support and adjustable relatively to the latter, said adjustable member being adapted to be moved into contact with the fixed member when the master-die is in its adjusted position, to arrest a subsequent movement of the die-support when a die thereon occupies the adjusted position of the master-die.

In testimony whereof I have affixed my signature in presence of two witnesses.

JAMES A. HORTON.
